United States Patent Office

Des. 212,534
Patented Oct. 29, 1968

212,534

COMBINED OTTOMAN AND TRAY UNIT

Martin Borenstein, 737 2nd St., Oakland, Calif. 94607

Filed Apr. 11, 1966, Ser. No. 1,851

Term of patent 14 years

(Cl. D15—8)

FIG. 1

FIG. 2

FIG. 3

FIG. 4

FIG. 5

FIGURE 1 is a perspective view of the ottoman showing my new design but with the central pillow removed exhibiting an underlying removable tray surface;

FIGURE 2 is a top plan view with the central pillow in position;

FIGURE 3 is a front elevational view;

FIGURE 4 is a rear elevational view; and

FIGURE 5 is a side elevational view, both sides being identical.

I claim:

The ornamental design for a combined ottoman and tray unit, as shown and described.
